PAPER CUTTING MACHINE

George W. Johnston, Astoria, N. Y.

Application October 20, 1936, Serial No. 106,497

9 Claims. (Cl. 164—41)

This invention relates to improvements in paper cutting machines in which a stack or pile of sheets, such as paper or card board, are supported upon a bed plate of the frame of the machine adapted to be simultaneously cut to size or trimmed by a cutter in the form of a knife blade carried by a carrier mounted in the frame to have reciprocatory movement toward and away from the bed plate, and relates particularly to power operated paper cutting machines embodying means to couple the cutter carrier actuating means with and uncouple it from power means and operative by means actuated when the cutter carrier actuating means moves the cutter away from the bed plate to uncouple the cutter carrier actuating means from the power means, and it is the object of the invention to provide improved means operative when the means to couple and uncouple the cutter carrier actuating means from its driving means is actuated to uncouple the cutter carrier actuating means from its driving or power means when the cutter carrier is moved away from the bed plate and hold the cutter carrier actuating means against movement and adapted to be released from the cutter carrier actuating means by the operation of the means to couple the cutter carrier actuating means with the power means.

In the drawing accompanying and forming a part of this application Figure 1 is a front elevation of a conventional form of paper cutting machine embodying the invention and showing the parts in operative position to hold the actuating means for the cutter carrier against movement, only so much of the paper cutting machine being shown as is essential to an understanding of the invention.

Figure 2 is a sectional view taken on the line 2—2 of Figure 1 looking in the direction of the arrows.

Figure 3 is a fragmentary front elevation of the machine and partly in section to show the parts embodying the invention in position to release the actuating means for the cutter carrier and permit of operation thereof to actuate the cutter carrier; and

Figure 4 is a fragmentary view of means to stop the cutter carrier actuating means after a cutting operation of the cutter.

An embodiment of the invention is illustrated in the drawing in connection with a conventional form of paper cutting machine, comprising a frame having a hollow base B arranged with a bed plate 4 for supporting the material, such as a stack or pile of sheets of paper or card board, to be cut or trimmed. An arched member 5 is mounted and supported upon the bed plate 4, the uprights of which arched member are provided with guideways in the form of slots for the engagement of a bar or carrier 6 for a cutter in

the form of a knife blade 7, the cutter being suspended in said guideways or slots to have reciprocatory movement toward and away from the material support by links 8, 9 pivotally connected at one end to the cutter carrier and at the opposite end pivoted to the arched member. There is provided the usual member to clamp the stack or pile of sheets to be cut to the bed plate adapted to be actuated toward and away from the bed plate by a hand wheel 10. A gauge or gauges (not shown) are also provided as usual to position the material on the support relative to the cutter.

A rotatable shaft 11 is journaled in the base of the frame and is adapted to be connected to driving means, shown in the form of a pulley 12 loose on the shaft and driven by a belt 13 from a suitable source of power, and shown as an electric motor M mounted on the frame of the machine. Means are provided to couple and uncouple the pulley 12 from the shaft 11, and shown as a conventional form of clutch comprising an expanding clutch arranged within the pulley and adapted to be operated by an expanding device 14 to engage a drum 14' carried by the pulley, 25 the expanding device 14 being actuated by a cone 15 mounted on the shaft 11 to have sliding movement on and rotate with the shaft and adapted to be moved or actuated toward and away from the expanding device 14 by a manually operative 30 lever or shifter 16 pivotally supported by a bracket mounted on the frame, the one arm of the lever having a bifurcation 17 to straddle the cone 15 and each bifurcation arm having a pin 35 fixed in and extending inwardly from said arms to engage an annular groove or recess in the cone 15, as shown at 18.

The shaft 11 is operatively connected to the cutter carrier 6 to move the same toward and away from the bed plate 4 by the rotation of the 40 shaft by a worm 19 on said shaft meshing with a worm wheel 20 fixed on a rotatable shaft 20' having a crank connection with the cutter carrier in the form of a link 21 pivotally connected at one end to a pin in a bifurcation of a laterally 45 extending portion of the cutter carrier, as at 22. The opposite end of the link 21 is pivotally engaged on a stud 23 fixed eccentrically in and extending laterally from a face of the worm wheel 20, whereby upon a revolution of the worm wheel 50 20, there will be imparted a movement to the cutter carrier toward and away from the material support. Means are provided to automatically stop the operation of the actuating means for the cutter carrier after each movement of the cutter 55 carrier toward and away from the material support or bed plate to permit of the removal of the cut or trimmed material and the substituting of material to be cut. For this purpose means are provided to disconnect the shaft 11 and 60

thereby the cutter carrier actuating means from the driving means 12, and shown as comprising an arm 24 pivotally connected at one end to and extending from an arm 33 of the clutch shifter 5 16 to intersect and lie contiguous to a face of the worm wheel 20, the arm being provided with an abutment 25 on the face thereof opposed to the worm wheel in the line of travel of a pin 26 fixed eccentrically in and extending laterally 10 from the face of the worm wheel and adapted to engage the abutment by the rotation of the worm wheel, when the clutch shifter is operated to actuate the cone 15 to connect the shaft with the driving means or pulley 12, and operate the clutch shifter 16 to actuate the cone 15 to disconnect the shaft 11 from the driving means or pulley 12. To facilitate reciprocating and counterbalancing the cutter carrier a further link 27 is pivotally 15 connected to the pin 22 and the opposite end connected to a pivoted counterweight, as is usual in machines of this character, but which is not shown since it does not constitute an essential part of the present invention.

To prevent movement of the cutter carrier 25 toward the material support or bed plate during the period of removal of the cut or trimmed material from the bed plate and substituting other material to be cut or trimmed, means are provided which is automatically operative to hold the 30 cutter carrier actuating means and thereby the cutter carrier against movement when the shifter lever 16 is operated by the arm 24 from the worm wheel 20 to actuate the cone 15 or by any other means, such as breakage in the clutch which will 35 actuate the cone 15 in a direction from the pulley 12, to disconnect the shaft 11 from the driving means or pulley 12 and thus prevent injury to the operator of the machine. This means as 40 shown comprises a lever, one arm 28 of which is provided with a nose 29 to arrange said arm as a latch. The lever is fixed on a shaft 30 extending parallelly of the axis of the worm wheel 20 and positioned so that the lever arm or latch 28 is juxtaposed to the face of the worm wheel from 45 which the stud 23 extends to which the link 21 is pivoted so that in one position of the lever latch 28 the nose will be positioned to be engaged by the extended end of said stud, as shown in Figure 1. To effect automatic operation of said 50 latch when the cutter carrier is moved to position away from the bed plate or material support and the shaft 11 disconnected from its driving means 12, the other arm 31 of the latch lever is connected with the clutch shifting lever 55 by a link 32 pivotally connected at one end to the lever arm 31 and the other end to the arm 33 of the clutch shifting lever.

In operation the parts are normally in the position shown in Figure 1 with the clutch shifting lever 16 positioning the clutch actuating member 15 in unclutching position and disconnecting the shaft 11 from the driving means 12. The pin 26 is in engagement with the abutment 25 on the arm 24 and the stud 23 is in engagement 60 with the nose 29 of the lever latch 28 with the cutter carrier in position away from the bed plate or material support and held in such position by the engagement of the stud 23 with the latch nose 29. In this position of the parts 65 the material to be cut or trimmed is positioned on the bed plate or material support 4 relative to the cutter when the clutch shifting lever 16 is operated to actuate the clutch member 15 to couple the shaft 11 with the driving means 12, 70 this movement of the clutch shifting lever 16

moving the arm 24 longitudinally and causing the abutment 25 to ride off from the pin 26 and flexing laterally the arm 24, the abutment having a beveled edge whereby this movement of the abutment is facilitated, and to actuate the lever 28, 31 in position to move the latch nose 29 out of engagement with the stud 23, and the blade carrier 6 is operatively connected with the driving means 12, as shown in Figure 3. The parts are maintained in such positions for substantially one revolution of the worm wheel 20 and during the movement of the cutter carrier toward and away from the material support. Just prior to the termination of a revolution of the worm wheel 20 the pin 26 will engage the arm abutment 25 and during the continued rotation of the worm wheel 20 and the engagement of said pin with the arm abutment 25 the arm 24 will be moved longitudinally toward the clutch shifter 16 and thereby move the clutch shifter 16 to 20 actuate the clutch actuating member 15 to permit the clutch to disconnect the shaft 11 from the driving means 12, and the parts will be effectively locked against movement in said positions by the stud 23 engaging the latch nose 29 25 of the lever arm 28.

Having described my invention, I claim:

1. In paper cutting machines, a support for the material to be cut, a cutter reciprocatory toward and away from the material support, means to actuate said cutter including a rotatable member adapted upon each revolution thereof to move the cutter toward and away from the material support, means to couple and uncouple said cutter actuating means with driving means therefor, and means operative by and upon a revolution of the rotatable member to uncouple the cutter actuating means from its driving means and hold the rotatable member against rotation with the cutter in position away from the material support.

2. In paper cutting machines, a support for the material to be cut, a cutter reciprocatory toward and away from the material support, means to actuate said cutter including a rotatable member adapted upon each revolution thereof to move the cutter toward and away from the material support, a clutch operative to connect the cutter actuating means with and disconnect the same from driving means therefor, a shifter for said clutch, means operative by and upon a revolution of the rotatable member to operate said shifter and actuate the clutch to disconnect the cutter actuating means from its driving means, and means operative by the movement of the shifter to disconnect the cutter actuating means from its driving means to engage and hold the rotatable member of the cutter actuating means against movement with the cutter in position away from the material support.

3. In paper cutting machines, a support for the material to be cut, a cutter carrier reciprocatory toward and away from the material support, a rotatable shaft, a clutch operative to connect and disconnect said shaft from driving means therefor, a clutch shifter, means to actuate the cutter carrier including a wheel rotatably driven by the shaft and a link pivotally connected eccentrically to said wheel and the cutter carrier arranged to move the cutter carrier toward and away from the material support upon a revolution of said wheel, means connected to the clutch shifter adapted to engage and hold the wheel, and means connected to the clutch shifter actuated by said wheel upon a revolution thereof to 75

5 operate the shifter to actuate the clutch to disconnect the shaft from its driving means and operate the wheel holding means to hold the actuating means for the cutter carrier against movement with the cutter carrier in position away from the material support.

4. In paper cutting machines, a frame including a support for the material to be cut, a cutter carrier mounted in the frame to have movement 10 toward and away from the material support, a rotatable shaft, driving means for and rotatable concentrically of the shaft, means to connect and actuate the cutter carrier from the shaft including gear wheels and a link connected at one end 15 to the cutter carrier and connected at the opposite end to a stud fixed eccentrically in and extending laterally from a face of one of the gears, a clutch to connect the driving means with and disconnect the same from the shaft, a shifter to 20 actuate said clutch, and a latch pivotally connected with the clutch shifter adapted to be engaged by the eccentric stud of the one gear when the shifter is moved to actuate the clutch to disconnect the shaft from its driving means and 25 said engagement of the stud with the latch holding the actuating means for the cutter carrier against movement, and the latch adapted to be released from said gear stud when the shifter is operated to actuate the clutch to connect the 30 shaft with its driving means.

5. In paper cutting machines, a frame including a support for the material to be cut, a cutter carrier mounted in the frame to have movement toward and away from the material support, a rotatable shaft having a worm thereon, driving means for the shaft, a clutch to connect and disconnect the shaft from the driving means, means to actuate the clutch, a worm wheel meshing with the worm on and rotated from the shaft 40 having a stud fixed eccentrically in and extending laterally therefrom, a link pivotally engaged at one end on the stud and at the opposite end connected with the cutter carrier and arranged to impart movement to the cutter carrier toward and away from the material support 45 upon a revolution of the worm wheel, and means connected with and operative from the clutch actuating means when operated to actuate the clutch to disconnect the shaft from its driving means to co-operate with the eccentric stud of 50 the worm wheel to hold said wheel against rotation and the cutter carrier against movement and said means being released from said stud when the clutch actuating means is operated to actuate 55 the clutch to connect the shaft with its driving means.

6. In paper cutting machines, a frame including a support for the material to be cut, a rotatable shaft having a worm thereon, driving means 60 for the shaft, a clutch to connect and disconnect the shaft from the driving means, a clutch shifter, a worm wheel rotatably supported by the frame meshing with the worm and having a stud fixed eccentrically in and extending laterally 65 therefrom, a link pivotally connected at one end to the cutter carrier and the opposite end pivoted on the stud of the worm wheel and arranged to impart movement to the cutter carrier toward and away from the material support upon a revolution of the worm wheel, means connected to 70 the clutch shifter and operative from the worm wheel upon a revolution thereof to operate the shifter to actuate the clutch to disconnect the shaft from its driving means, and a latch con-

nected to the shifter adapted to engage the link connecting stud and hold the worm wheel and cutter carrier against movement when the shifter is operated to actuate the clutch to disconnect the shaft from the driving means, and 5 release the latch from said stud by the operation of the shifter to actuate the clutch to connect the shaft with its driving means.

7. Paper cutting machines as claimed in claim 6, wherein the latch comprises an arm of a lever 10 connected to the clutch shifter by a link pivotally connected to the other arm of said lever and the shifter.

8. In paper cutting machines, a frame having a support for the material to be cut, a cutter 15 carrier mounted in the frame to have movement toward and away from the material support, means to actuate said cutter carrier including a rotatable wheel having a stud fixed eccentrically in and extending laterally from the wheel and a 20 link pivoted at one end on said stud and the opposite end connected with the cutter carrier to impart movement to the cutter carrier toward and away from the material support upon a revolution of the wheel, driving means, means including a clutch to connect the wheel with and disconnect the wheel from the driving means, a clutch shifter, a lever having one arm arranged as a latch to engage the wheel stud to hold the wheel and cutter carrier against movement, and 25 a link connecting the other arm of the lever to the clutch shifter, and said shifter when operated to actuate the clutch to disconnect the wheel from the driving means adapted to position the latch to be engaged by the wheel stud and when 30 operated to actuate the clutch to connect the wheel with the driving means actuate the lever to release the lever latch from the wheel stud.

9. In paper cutting means, a frame including 40 a support for the material to be cut, a cutter carrier mounted in the frame to have movement toward and away from the material support, means to actuate said cutter carrier including a rotatable wheel having a stud fixed eccentrically 45 in and extending laterally from the wheel and a link pivoted on said stud at one end and connected at the opposite end with the cutter carrier to impart movement to the cutter carrier toward and away from the material support upon a revolution of the wheel, driving means, means including a clutch to connect the wheel with and disconnect it from the driving means, a clutch shifter, an arm connected to and extending from the clutch shifter to intersect and lie 50 contiguous to a face of the wheel and having an abutment on the face opposed to the wheel, a pin fixed eccentrically in and extending from the wheel adapted to engage the arm abutment upon a revolution of the wheel and thereby move 55 the arm and shifter to actuate the clutch to disconnect the wheel from the driving means, a lever having one arm arranged as a latch to engage the wheel stud to hold said wheel and the cutter carrier against movement, and a link connecting the other arm of said lever to the 60 clutch shifter, and said shifter when operated to actuate the clutch to disconnect the wheel from the driving means adapted to position the lever latch to be engaged by the wheel stud and when operated to actuate the clutch to connect the 65 wheel with the driving means actuate the lever to release the lever latch from the wheel stud.

GEORGE W. JOHNSTON.
